UNITED STATES PATENT OFFICE.

CLARA G. SMITH, OF BOSTON, MASSACHUSETTS, ASSIGNOR TO JACOB HIRSHFELD AND HENRY F. SAMSTAG, OF NEW YORK, N. Y.

DESIGN FOR A BODY FOR BELTS OR SIMILAR ARTICLES.

SPECIFICATION forming part of Design No. 32,892, dated June 26, 1900.

Application filed May 23, 1900. Serial No. 17,760. Term of patent 7 years.

To all whom it may concern:

Be it known that I, CLARA G. SMITH, a citizen of the United States, residing at Boston, in the county of Suffolk and State of Massachusetts, have invented and produced a new and original Design for a Body for Belts or Similar Articles, of which the following is a specification, reference being had to the accompanying drawing, forming a part thereof.

10 The drawing represents a view in elevation of a body for belts or similar articles, illustrating my design.

15 The leading feature of my design for a body for belts or similar articles consists of an elongated center piece having broad ends and straight side edges converging therefrom toward its middle and oppositely-extended loops, the broad and flat overlapped side portions of which diverge from their bights and

20 join the intersecting side edges of the transversely-arranged center piece, the side portions of each loop being substantially at right angles to the adjacent side edges of the center piece, from which they respectively extend,

25 the body as a whole tapering gracefully and gradually from the center piece outwardly to the bights of the loops. The elongated center piece a is shown as having broad upper and lower ends a' a'' and side edges a^{10} a^{12} ,

30 the former converging from the upper end and the latter from the lower end toward the

middle of the center piece, and oppositely-extended loops B , located at each side of the transversely-arranged center piece. Each loop is formed by a broad flat band turned 35 back upon itself, so that its side portions b b' overlap and diverge from the bights b^2 , said side portions being substantially at right angles to the adjacent side edges a^{10} a^{12} of the center piece, from which they respectively extend. Ornamental buttons c are located at the outer ends of the edges a^{10} a^{12} and similar ornaments c' at the intersection of each pair of side edges at the middle of the center piece. The uppermost side portion of 40 each loop is exposed to view in its entirety, overlapping and partly concealing the under side portion thereof.

Having fully described my design, what I claim, and desire to secure by Letters Patent, 50 is—

The design for a body of a belt or similar article substantially as herein shown and described.

In testimony whereof I have signed my name to this specification in the presence of two subscribing witnesses.

CLARA G. SMITH.
